J. T. SIBLEY,

COMBINED TONE ARM AND STOP DEVICE FOR TALKING MACHINES.

APPLICATION FILED JULY 9, 1917.

JAMES T. SIBLEY, OF NEWARK, NEW JERSEY.

COMBINED TONE-ARM AND STOP DEVICE FOR TALKING-MACHINES.

1,313,342.

Specification of Letters Patent. Patented Aug. 19, 1919.

Application filed July 9, 1917 Serial No. 179,365.

To all whom it may concern:

Be it known that I, JAMES T. SIBLEY, a citizen of the United States, residing in the city of Newark, county of Essex, and State 5 of New Jersey, have invented certain new and useful Improvements in Combined Tone-Arms and Stop Devices for Talking-Machines, of which the following is a specification.

10 The tone arm which forms the subject matter of my invention contains several novel features, as for example, a self-contained adapter whereby the sound box mounted upon the free end of the tone arm 15 may be made to occupy several positions corresponding with the requisites necessary to play the three general classes of records with the same sound box.

Phonograph records are classified by the 20 manufacturers into two general types. The first type is known as the "zig zag" record, wherein, the record groove has a laterally undulating spiral groove of uniform depth. The second type is known as the "hill and 25 dale" type of record, wherein, the record groove is a spiral of nonuniform depth. The term "hill and dale" aptly describes this type of record. The second type may be further subdivided into two subtypes of 30 records according to the character of the cutting stylus which forms the groove. The well-known Edison record belongs to the first subtype, wherein the groove is formed by means of a button or gouge stylus; it is 35 substantially circular in cross section. The second subtype includes the well-known Pathé record in which the record groove is cut with a pointed stylus to a varying depth, but without lateral undulation.

40 In reproducing records of the first type the best results are obtained by mounting the sound box with its diaphragm in a plane perpendicular to the plane of the record and with the stylus bearing upon the record at 45 an inclination of from 30, to 40, degrees from the perpendicular. With the Edison record the best results are obtained by arranging the diaphragm of the sound-box in a plane parallel to the record and with the stylus 50 slightly out of perpendicular to the plane of the record. With the Pathé type, the best results are obtained by arranging the diaphragm in position, so that its plane will cut the plane of the record at an angle of 55 from 50 to 60 degrees, with probably the best results obtained at 54 degrees. Numer-

ous attempts have been made to make a single adapting device whereby, records of the gramophone or laterally undulating type, and also the so called Pathé records could 60 be played by shifting the position of the sound-box upon the end of the tone arm. Again means have been provided for adapting the sound-box to play both records of the lateral undulating type, and also of the 65 so called Edison type, by shifting the sound-box from a plane perpendicular to the face of the record to the plane parallel to the face of the record. I am not aware however, that the combination in the same means, 70 has ever provided for playing all three of the aforesaid types of records, and, it is the object of my invention to provide such means in a single unitary tone-arm.

A further object of my invention is to 75 provide means in connection with the tone arm whereby whenever the tone arm and sound-box are in playing position the motor will be set in operation and when the tone arm is swung to the side of the record 80 and released, with the sound-box free from the record, then the motive power will be completely cut off.

I have also provided a novel ball bearing 85 for the tone arm whereby, the same is rendered very much more free in its movement and consequently creates far less drag upon the motor.

In carrying out my invention I make use 90 of the structures described in the following specification and illustrated in the accompanying drawings wherein,

Figure 1, is a side elevation of my improved tone arm and stop device.

Fig. 2, is a plan view of the same.

Fig. 3, is a fractional side elevation of the 95 free end of the tone arm illustrating the position of the parts assumed when playing a Pathé record.

Fig. 4, is a side elevation partly in section 100 showing the means for locking the parts of the adapter in place.

Fig. 5, is an enlarged vertical section of the tone arm bearing, also showing the circuit breaker connections.

Fig. 6, is a section of the sound-box relieving mechanism for relieving a portion 105 of the weight of the sound-box upon the record.

Similar reference numerals refer to like 110 parts throughout the specification and drawings.

The tone arm consists of the L-shaped tapered member 1, and its pivoted sound-box extension 2, to which the tubular adapter member 3, is secured, from which latter the sound-box elbow 4, also extends. The supporting member 5, is provided with the flat flange 6, by which the same is secured to the motor board 7, by the several screws 8. This supporting member is provided with the upwardly extending thimble 9, having its upper margin chamfered or beveled as at 10. It is also provided with the annular upwardly extending flange 11, to which the overhanging angular ball bearing ring 12, is adjustably secured by means of the set screws 13. The lower end of the tone arm member 1, has an outwardly flaring inclined flange 14, at its lower margin, and said flange 14, together with the flange 11, and the ring 12, form a raceway for the lower set of balls 15. The interior of the lower end of the tone arm member 1, is enlarged so that it may slip over the tubular thimble 9. It is also provided with the shoulder 16, which in conjunction with the beveled part 10, of the thimble 9, forms a race-way for the balls 17. In this manner I provide a very efficient ball-bearing for the tone arm member 1, upon the supporting member 5.

30 The outer end of the tone arm member 1, is provided with a pair of forwardly extending lugs 18, between which the ball 19, is supported, by means of the trunnions 20, the purpose being to form a species of ball and socket joint between the members 1 and 2, of the tone arm.

35 The member 2, of the tone arm extends forwardly and downwardly as shown, into the free end of which the obtuse-angled elbow member 3, is fitted and permitted to oscillate about the common axis. The sound-box member 4, is a short rectangular elbow section fitted into the free end of the member 3, against the shoulder 22, and about 40 which it may oscillate to a limited extent. The elbow member 3, is provided with a circumferential slot 23, having the enlarged circular ends 24. This slot extends around the end of the member 3, about 90 degrees. In 45 this slot is located a headed spring pressed bolt 25. The inner head 21, of this bolt is tapered to fit snugly the enlargements 24, at the ends of the slot 23. The outer end of the bolt extends somewhat beyond the member 3, and is provided with the detachable head 25', between which and the side of the member 3, is located the spring 26, the structure being such that when the tapered head is inserted into one of the enlargements 24, of the slot, the member 3, is locked in place in the end of the member 2; but upon pressing the bolt inward the parts are unlocked and the member 3, may be turned to a position for the head to engage 55 the other enlargement. The sound-box el-

bow 4, is connected to the member 3, in identically the same manner, such elbow being provided with the slot 23, with the enlargements 24, in the ends thereof to receive the tapered head 21, of the bolt 25, with the 70 spring 26, pressed upon the outer side of the member 3, and against the outer head of the bolt 25'. By this arrangement the member 3, may be made to occupy two positions for example, the position shown in 75 Figs. 1, and 2, and the position shown in Fig. 3. In the position shown in Fig. 1, the axes of the two members 2, and 3, lie in the same vertical plane. In the position shown in Fig. 3, the member 3, is turned through 80 an angle of 90 degrees with its outer end turned laterally. In the position indicated in Figs. 1, and 2, the elbow member 4, may be made to occupy two positions, one in which the free end is turned laterally or 85 horizontally to receive the sound-box 30, with the diaphragm thereof in the vertical plane. In the other position the free end of the member 4, is turned down with the diaphragm of the sound-box 30, parallel 90 to the plane of the record 31. In this case the stylus needle is presented in the substantial vertical position to the record or at right angles to the stylus lever so that in this position Edison records may be played. 95 In the position shown in Figs. 1, and 2, with the sound-box diaphragm in a vertical plane or the plane perpendicular to the plane of the record, the lateral undulating type of record may be played. When the member 10 3, is turned laterally as illustrated in Fig. 3, the elbow member 4, may be turned upwardly at an angle of between 30 and 40 degrees to the plane of the record, in which position the diaphragm of the sound box 10 will be in a plane at an angle of between 50 and 60 degrees to the plane of the record, in which position records of the Pathé type 11 may be played. So that with the members 2, 3, and 4, coupled together and of the angular form shown, the three several positions requisite to playing the three types of records may be assumed by the sound-box.

In my prior application, Serial No. 175-565, filed June 19, 1917, I have illustrated 11 and described an electric motor for driving the turntable of talking machines, in which a switch, located in the electric circuit is diagrammatically shown. The tone arm above described is admirably adapted for 1 use in connection with the said electric motor and the electric circuit for operating such motor may be connected up to this tone arm in such a manner that when said tone arm is in playing position, with the sound-box 1 stylus needle resting upon the surface of the record to be played, the switch will be closed. When the tone arm is swung to the side of the record and the member 2, released, the weight of said overhanging member 3, and 1

the sound-box is utilized to open this switch and thereby cut off the motive current from the motor. This function is accomplished by the following mechanism:

- 5 Mounted upon the ring 12, is an arc-shaped piece of insulating material 32, arranged concentric to said ring as shown and secured in place by means of the screws 33. Upon the outer face of this insulating material is secured a contact strip 34, extending to a considerable distance, as shown, with one of its ends connected up by means of the wire 35, to the electric circuit which includes the motor 36, the other section of 10 the circuit from the motor being grounded upon the supporting member 5, or upon any other metallic part of the tone arm. Extending diametrically through the bottom part of the member 1, and following the 15 general contour of the under side of said member is a rod 37. This rod is guided in diametrical apertures 38, and 39, in the member 1, and also in an apertured bracket 40, upon the under side of said member 1. 20 Upon the outer free end of said rod 37, is located a contact piece 41, in position to engage the contact strip 34, and in order to insure such contact I provide a collar 42, upon said rod upon the opposite side of the 25 member 1, and surround the rod 37, between said collar 42, and the body of the member 1, with a spring 43. This always insures contact between the contact piece 41, and the strip 34. The rod 37, extends as above, 30 noted, horizontally through the bracket 40, to a point beneath the trunnion 20. Extending downwardly from the ball 19, is an arm 44, in position to engage the free end of the rod 37, adjacent thereto. It will be noted 35 that whenever the member 2, is raised to carry the arm 44, clear of the end of the rod 37, then the spring 43, will reciprocate the rod 37, and bring the contact piece 41, into contact with the strip 34, thereby closing 40 the circuit. When, however, the member 2, is permitted to swing downwardly upon the trunnions 20, as for example, when the tone arm is swung free from a record and the sound-box permitted to drop by its own 45 weight then the arm 44, will swing into contact with the free end of the rod 37, and since the leverage is sufficient, the rod 37, will be pushed endwise, thereby compressing the spring 43, and carrying the contact piece 50 41, clear of the contact strip 34. In the playing position illustrated in Fig. 2, the arm 44, is completely free from the end of the rod 37, and only contacts with such rod when the sound-box, together with the members 2, 3, and 4, drop downwardly, but this 55 can only occur when the sound box is clear of the record.

In order that the weight of the sound-box may be slightly relieved from the record, I 60 mount upon the end of the rod 37, a sleeve 65

45, said sleeve being counterbored as at 46, to receive the spring 47, which is located upon the rod 37, between the shoulder 48, of said sleeve and the bracket 40. The opposite end of the sleeve is counterbored as at 49, and the headed screw 50, is screwed into the end of the rod 37. The spring 47, is insufficient to overcome the entire weight of the tone arm members 2, 3, and 4, together with the sound-box, yet it is sufficient to 70 relieve the record of a portion of such weight. In the playing position illustrated in Figs. 1, and 6, the spring 47, is slightly compressed. If the sound-box is lifted free from the record by swinging the elements 75 2, 3, and 4, upwardly upon the trunnion 20, the arm 44, will be carried clear of the end of the sleeve 45, and the spring 47, will expand to the extent permitted by the head 50. On the other hand the sleeve 45, being 80 simply mounted upon the rod 37, does not interfere with said rod when the arm 44, swings sufficient to contact with the head 50, and if the movement of the arm 44, is sufficient the circuit will be broken between the 85 contact 41, and strip 34, as above described. The length of the strip 34, is sufficient to maintain this contact during the playing of the entire record. I regard this as an important feature of my invention, for the 90 reason that no attention to the motor is necessary; the swinging of the sound-box and tone arm into playing position and lowering of the member 2, with the stylus needle upon the record closes the circuit 95 through the motor and starts the same, while the swinging of the sound-box and tone arm free from the record and releasing the sound-box serves to immediately break the 100 circuit and stop the motor.

105

In order to regulate the tension of the spring 47, I may provide the longitudinally apertured screw 51, through which the rod 37, may slide, screwing said screw into the bracket 40, against the end of the spring 47. 110 In this manner, I may adjust the tension of the spring 47, and consequently the amount of its relieving effect upon the weight of the members 2, 3, and 4, and sound-box 30.

It will thus be seen that I have embodied 115 in a single structure, not only means for adapting the sound box to the several classes of records now on the market, and also an admirable form of bearing for the tone arm, but more important still, a switch 120 and stop mechanism applicable not only to the motor of my prior application, above described, but also to any electric motor used for operating the talking machine.

In the position shown in Figs. 1, and 2, 125 the contact strip 34, is of such length that further movement of the tone arm will cause the contact 41, to leave the strip 34, and bear upon the insulation 32, after it has been swung to a considerable distance to the 130

side of the record, so that even if the member 2, and sound-box 30, are lifted to replace a stylus needle, the circuit will be broken and the motor consequently not started, by 5 reason of the action of the spring 43, upon the rod 37. This is as it should be for the motor should not start until the sound-box and tone arm are in playing position with the stylus needle upon the record.

10 I claim:

1. In a tone arm for talking machines, the combination of a horizontally swinging sound tube having its pivot end outwardly flared to form a lower ball bearing seat and 15 an internal annular shoulder forming an upper ball bearing seat, a supporting member having a tubular part which telescopes into, and forms a ball raceway between its upper end and said shoulder, and a ball retaining ring secured to said supporting member to form with said ball bearing seat a ball raceway; and separate sets of balls in 20 said raceways respectively.

2. In a tone arm for talking machines, 25 the combination of a horizontally swinging sound tube and a support therefor, upon which said sound tube telescopes, a bearing between said tube and support comprising upper and lower ball raceways with 30 balls therein, the upper raceway formed by an annular shoulder upon the interior of said tube and the upper end of said support, and the lower raceway formed by a flaring flange upon the lower end of said tube and a 35 ball ring secured to said support and surrounding the lower end of said tube.

3. In a tone arm for talking machines, the combination of a horizontally swinging sound tube, with a tubular extension mounted upon 40 the free end of said tube for vertical oscillation, an electric circuit, and means actuated by the vertical oscillation of said tubular extension to open and close said circuit.

4. In a tone arm for talking machines, the combination of a horizontally swinging 45 sound tube, having a tubular extension pivoted to the free end thereof for vertical oscillation, an electric circuit having a switch therein, means actuated by the upward oscillation of said extension to close 50 said switch, and by the downward movement of said extension to open said switch.

5. In a tone arm for talking machines, the combination of a horizontally swinging sound tube having a vertically oscillating 55 tubular extension at the free end thereof, an electric circuit having a translating device and a switch therein, means actuated by the upward movement of said extension to close 60 said switch.

6. In a tone arm for talking machines, the combination of a sound tube having a tubular extension pivoted for vertical oscillation at the free end thereof, a support for said tube about which it may swing in a horizontal plane, a reciprocating rod carried by said tube, means upon said tubular extension for moving said rod endwise in one direction, and a spring for moving said rod endwise in the opposite direction, an electric 70 circuit having a translating device therein, and means actuated by the downward movement of said tubular extension and the endwise movement of said rod to break said circuit.

7. In a talking machine, the combination of a horizontally swinging tone arm, having a vertical swinging extension thereon, an electric circuit, and means actuated by the downward swing of said extension to break 80 said circuit, and by an upward movement thereof to close said circuit, and to break said circuit in any position of said extension upon a lateral swing of said tone arm beyond a predetermined point.

JAMES T. SIBLEY.
